F. MEYER

DOOR OPENING AND CLOSING DEVICE

Filed Feb. 10, 1923

INVENTOR.

*Fred Meyer
Chattanooga*

ATTY

UNITED STATES PATENT OFFICE.

FRED MEYER, OF PEKIN, ILLINOIS.

DOOR OPENING AND CLOSING DEVICE.

Application filed February 10, 1923. Serial No. 618,290.

To all whom it may concern:

Be it known that I, FRED MEYER, a citizen of the United States, a resident of Pekin, in the county of Tazewell and State of Illinois, have invented new and useful Improvements in Door Opening and Closing Devices, of which the following is a specification.

This invention has reference to door opening and closing devices, and has for its principal object to provide a simple, inexpensive and yet effective device of this character applicable particularly to garage doors, and including means for operating such a device within the garage, or at a suitable point removed therefrom; whereby, when approaching the garage the driver of an automobile may open the garage doors without alighting from the car.

The invention has for a further object, spring means to assist in moving the doors to open and also closed position, after a predetermined movement of the operating means, and also means for holding the doors in open position against accidental closing, due to wind pressure.

That the invention may be more fully understood, reference is had to the accompanying drawings forming a part of the present description, illustrating a preferred embodiment of the invention, in which:

Figure 1 is a top plan view of my improved door opening and closing device applied to garage doors, the garage being shown in dotted lines in a diagrammatic way, with the garage doors in full lines, closed;

Figure 2 is a view similar to Figure 1, except that the doors are in open position and the door opening device also moved to open position, and

Figure 3 is a detail of parts of the device, as the same would appear, if taken on the line 3—3 Figure 2.

Like characters of reference denote corresponding parts throughout the figures.

In providing a door opening and closing device for a garage, or similar building, it will be understood that the door operating means must be so located that an automobile, car or truck moving into and out of the building will not encounter such device, or interfere with it, or be interfered with, and therefore, even though I have elected

to show the device immediately beneath the ceiling of the building and within the interior of the building, it could conveniently be located in a compartment below the floor of the building and be operated with as good results. And while I have shown the garage as having two hinged doors, the omission of parts will enable it to be connected to one door and operated with as good results.

The garage or other building is designated A, being preferably shown in dotted lines, except the two doors, B, B hinged thereto and adapted to be swung toward and from each other. A supporting beam C is shown to which are connected certain operative parts of the device.

1, 1, designate similar connecting bars which have a suitable pivotal connection, at 2, with the doors B, and normally converge to a meeting point and have a pivotal connection with a control rod 3 connected to swing freely from the beam C. The meeting point of the bars 1, when in closed, as well as when in open position, controlled by the rod 3, is at a point on an imaginary line passing through the center of the garage and intersecting the meeting edges of the doors B, see Figures 1 and 2. In practice the meeting ends of the bars, when the doors are closed, is at a point, preferably in the rear of the beam C, and when the doors are opened, at a point, preferably in the front of the beam C. The rod 3 has the opposite angular ends 4 and 5. The former to provide for a pivotal connection with the beam C, and the latter to provide for the connection of the bars 1, 1, therewith, and also a link 6 and a rod 7 forming a connection for a coil spring 8, the rod 9 from the opposite end, of which, has a pivotal connection with the beam C.

To the beam C, and to one side of the device, is journaled a pulley wheel 10, over which is guided a rope or cable 11, the inner end of which is connected to the link 6 and the forward portion of said rope or cable leads to one side of the garage, just inside the door, and passes over one or more guide pulleys 12 and 13, with a section, not shown, depending within reaching distance inside the garage, and the section 11^a passing out through the wall of the garage and led to a point in advance thereof where it passes

down over a guide pulley 14 on a post D, being within the grasp of a driver of a car approaching the garage, who may pull on the cable or rope to open the doors B without alighting from the car.

In the operation of the device, the doors being closed, as in Figure 1, and it being desired to open the same, as in Figure 2, a pull on the rope or cable 11 will move 10 the bars 1 outwardly, their inner pivotally connected ends swinging in an arc of a circle described by the outer end of the control rod 3 swinging on its pivot on the beam C, and due to such movement the doors B 15 are started moving to open position. At the same time the pull is against the tension of the spring 8 which expands, until it is swung across the pivot of the rod 3, with the beam C. When said spring contracts, 20 pulling the connected ends of the bars 1 and the end of the control rod 3 into the position shown in Figure 2, resulting in the doors B being forced to the full open position shown in said Figure 2, and held in 25 such position and prevented from closing due to wind pressure.

To close the doors B, a corresponding pull on the rope or cable 11 will cause the control rod 3 to retraverse its path of travel, 30 drawing the bars 1 inwardly and swinging their inner ends in an arc of a circle described by the movement of the outer end of the control rod 3, again expanding the spring 8, which, as soon as it crosses the 35 pivot point of the rod 3 with the beam C will contract, pulling the connected ends of the bars 1 and the end of the control rod 3 into the position shown in Figure 1, resulting in the doors B being closed, as shown

in said Figure 1, and held in such closed 40 position.

It is obvious that the location of the rope or cable and control rod and spring may be initially placed at either side of the building and operate with as good results. It 45 is also obvious that if only one door is used, one of the bars 1 could be omitted, and the device used with equally as good results.

The device is simple, inexpensive, effective and may be conveniently applied and operated by an unskilled person or child. The slightest pull will position the parts so that the full opening or closing of the doors will have the assistance of the spring 8, as 55 will be understood.

What I claim is:—

In a door opening and closing device, in combination, a pivotal control member, a pair of bars, each connected to a door and converging to and connected with the swingable end of said member; a rope or cable connected to the swingable end of said member and guided by a pulley located at one side of said bars, and a spring for positioning said member, whereby its outer end and the connected ends of said bars will intersect an imaginary line at their two extreme movements, said spring adapted to expand through a partial swing of said 70 member and to contract through the remainder of the swing of said member, when said member is swung either forward or back.

In witness whereof, I have hereunto 75 affixed my hand this 7th day of February, 1923.

FRED MEYER,
